United States Patent

Des. 239,319
Patented Mar. 23, 1976

239,319

ROTARY ACTUATOR

Stephen Matousek, and Ulrich H. Koch, Moraga, Calif.,
assignors to Whitey Research Tool Co., Emeryville,
Calif.

Filed May 19, 1975, Ser. No. 578,758

Term of patent 14 years

Int. Cl. D15—99

U.S. Cl. D55—1 G

FIG. 1

FIG. 3

FIG. 2

FIG. 4

FIG. 5

FIG. 1 is a side elevational view of a rotary actuator showing our new design;

FIG. 2 is an end view thereof taken from the right side of FIG. 1;

FIG. 3 is an end view thereof taken from the left side of FIG. 1;

FIG. 4 is a top plan view thereof, the bottom view being a mirror image of the top plan view; and

FIG. 5 is a view thereof taken along lines 5-5 of FIG. 4.

We claim:

The ornamental design for a rotary actuator, as shown.
